HOUSING FOR CURRENT AND VOLTAGE
REGULATORS

Charles W. Musser, Omaha, Nebr., assignor to
Jubilee Manufacturing Company, Omaha,
Nebr., a corporation of Nebraska

Original application July 1, 1940, Serial No.
343,349. Divided and this application Septem-
ber 7, 1940, Serial No. 355,774

2 Claims. (Cl. 175—336)

This invention relates to the ignition systems of automobiles and the like and more particularly to such current and voltage regulators therefor which have electro-magnetic coils, the cores of which are each of two-piece construction and adjustable according to the potential differences of the electrical current output of any one of several conventional automobile generators to which a regulator may be electrically connected for governing said output, one of said two pieces of each said core being vibratable and the other rotatable and longitudinally adjustable for increasing or decreasing the distance between said pieces for correspondingly affecting said governing.

A particular object of the invention is to provide a housing for said regulator mechanism which includes a part of said mechanism and so cooperatively assembled and constructed, and sealed that an adjustment of a rotatable core part of said mechanism is permitted without breaking said seal or disassembling said housing.

Other and further objects and advantages of the invention will be understood from the following detailed description thereof, reference being had to the accompanying drawings in which:

Figure 1 is a front elevation of the new device, a certain portion thereof being broken away and in section, a door employed being shown in open position.

Figure 2 is a top plan view thereof, certain portions being broken away, and said door in a closed position.

Figure 3 is a transverse section taken on line 3—3 of Figure 2.

Figure 4 is an enlarged top plan view of said vibratable and rotatable core parts assembled with an electro-magnetic coil.

Figure 5 is an edge view of a detent for a rotatable core part.

Figure 6 is a plan view of said detent.

The mechanism which provides a portion of the housing of the present invention is more particularly described in my co-pending application, Serial No. 343,349, filed July 1, 1940, the title of said application being Current and voltage regulator, the present application being a division thereof. It was ascertained during a marketing of several thousand of the said mechanism that the interests of motorist-users thereof were best served by permanently adjusting and sealing certain parts of said mechanism at the factory and by skilled operators together with disposing said mechanism within the sealed housing of the present invention, whereby unskilled and unauthor-

ized persons would be prevented from tampering with the said permanent adjustments and the adjustment of that certain core part of the mechanism which is required to be adjusted complementary to a particular generator and at the time of electrically connecting a mechanism to said generator would be permitted, and the present invention aims to provide such a particular housing for said mechanism that an adjustment of a certain rotatable core part of said mechanism is permitted without breaking the seal of said housing.

In the drawings 20 indicates a metallic ground plate provided with a perimetrically disposed flange 21, the latter having suitable screws 22 for attaching the plate 20 to an automobile engine in a position of use. The several parts of the said mechanism are electrically connected to the electrical system of an automobile as more particularly described in my said co-pending application.

A slab of insulation 23 which forms a part of the housing of the present invention is provided with a medially disposed recess 24. The slab is 25 suitably secured to the plate 20 by means of rivets 25 said slab having a perimetrically disposed step 26. A cover portion of the housing is indicated at 28, said cover being provided with a top, side and end walls and an open bottom. The 30 perimetal edge 27 of said bottom is snugly received in the step 26 and when so assembled the cover together with the slab 23 provides said housing for certain permanently sealed portions of electrical instrumentalities of said mechanism 35 disposed between the top of said cover and said slab. The cover is secured in the said position to the base or ground plate by means of one or more screws 29 which, as best shown in Figure 3, have threaded lower ends 30 received in said 40 plate. As best shown in Figure 1 the heads 31 of the screws are disposed within recesses 32 provided in the top of the cover 28. After said permanent adjustment of certain portions of said mechanism, the cover 28 being disposed and secured as above described, sealing wax 33 is adhesively engaged with the heads 31 of said screws and adjacent portions of the walls of their respective recesses for sealing said cover to the slab 23, said wax being protectively disposed within said 50 recesses which insures against a breakage of said wax by contact with foreign objects. As best shown in Figure 1, the front wall of the cover 28 is provided with an aperture 34 and a door 35 for normally closing said aperture is pivotally mounted as at 36 whereby at times when the door

is swung to the position thereof shown in Figure 3 the aperture 34 is snugly closed. The annular wall of the aperture 34 is provided with an inwardly disposed finger or indicator 37 for purposes later described.

A current regulator coil 38 is disposed approximately medially of the longitudinal length of the slab 23 and as more particularly shown in the said copending application a voltage regulator coil 39 is disposed at one side of the coil 38 and a cut-out shunt coil 40 at the other side thereof. The windings of the coil 40 are disposed within a cut-out series coil 41. The coils 40 and 41 are provided with a core 42 which is common to said coils and said core is similar in construction with respect to the core 43 of the coil 38 and also similar with respect to the core 44 of the coil 39. Each of said three cores is of two piece construction whereby an air gap is provided between said two pieces of each core. Each core includes a rotatable piece and a vibratable piece. The rotatable pieces for the coils 39 and 40 are permanently adjusted at the factory and sealing wax then applied thereto as indicated at A in Figure 2, said sealing wax A being adhesively secured to the rotatable core and to later described spring detents therefore.

The current regulator coil 38, as shown in Figure 3, is disposed around a sleeve of insulation 45 and a disk of insulation 46 is provided at each end of said coil and between the latter and the respective adjacent supports which include a metallic L-shaped pole piece 47 and a plain pole piece 48. The shorter arm 47' of the pole piece 47 is connected to and in contact with the pole piece 48, said pole pieces extend through the slab 23, being connected together by means of a terminal 49, the latter being disposed within the recess 24 of the slab 23 whereby the pole pieces 47 and 48 together with the terminal 49 provide a magnetic field for the coil 38 for energizing the core of said coil at times when an electrical circuit is closed, during use, through the coil 38.

The core part 43' is provided with a boss 50 formed of non-magnetic material such as brass. The boss 50 extends beyond the inwardly disposed end of said core part 43' for preventing a physical contact between the core parts 43 and 43' at all times, said boss preferably consisting of an end of a rivet which extends through the core portion 43', the head of said rivet being peened to a spring-arm 51 for mechanically securing said arm and core part together whereby magnetic induction is permitted between the core parts 43 and 43' and physical contact thereof prevented, said boss 50 preventing the core parts from "freezing" or adhering together at times when an electrical circuit is closed through the coil 38.

As best shown in Figure 4 the core parts 43 and 43' are in approximate alignment and disposed oppositely within the sleeve 45.

The core part 43 is longitudinally adjustable with respect to the vibratable core part 43', being provided with a screw thread 53, the latter being complementary to a screw thread provided on the pole piece 47 through which the core part 43 extends and in a manner whereby the part 43 may be rotated for providing a minute adjustment of the space between the oppositely disposed ends of the core parts 43 and 43' for adapting the coil 38 to a particular generator to which it is electrically connected.

The outer end of the core part 43 is provided with a slot 54 adapted to receive a screw driver bit therein for facilitating a rotation and minute

adjustment thereof at times when the door 35 is in an open position.

A dial 60 is axially secured adjacent said slotted end of the threaded shaft core part 43, said dial 5 having a face adjacent to said door which is provided with radially disposed figures thereon for denoting a degree of adjustment and rotation of the core part 43 in conjunction with the cooperative finger 37 provided on the wall of the aperture 34 of the cover.

A particular detent means is employed for holding the core part 43 in a selected position of adjustment. Said detent means includes a spring-steel strip 55 which is provided at each 15 of its sides with a hook portion 56, said hooks, as best shown in Figure 4, being disposed over the side edges of and clamped to the pole piece 47 whereby the strip 55 is prevented from rotating at times when the core part 43 is rotated during an adjustment of the latter with said screw driver.

As best shown in Figure 6, the strip 55 is provided with a medially disposed aperture 57 through which the threaded part 53 of the core 25 43 extends. As best shown in Figure 5, the side walls of the aperture 57 provide a pair of outwardly and oppositely disposed resilient tangs 58 and 59 since said strip preferably is formed entirely of spring steel.

As best shown in Figure 4, the tang 58 engages 30 on one side of a convolution of the thread 53 of the core part 43 and the tang 59 on the opposite side of said convolution. As thus described it will be noted that the free ends of the tangs 35 become moved from the normal aligned position thereof shown in Figure 5 to the cooperative position of use and non-alignment thereof, as shown in Figure 4, when applied to a convolution of the thread 53, said applying being consummated 40 by rotating the shaft core part 43 through said tangs during an assembly of the mechanism, said movement of said tangs with respect to each other causing said tangs to be deformed for firmly gripping said convolution and preventing rotary movement of the core part 43 incident to shocks and jars generated during a road traveling movement of an automobile or the like.

As shown in Figure 4, and as more particularly described in said co-pending application one end 55 of the spring-arm 51 is secured by means of rivets 61 to a bi-metallic portion of the arm 51, said portion consisting of two oppositely disposed pieces of metal 62 and 63 each of which has a different thermal characteristic for providing a thermostatic device which is secured by means of screws 64 to the plain pole piece 43, being spaced from the latter by means of terminals B and C whereby the core part 43' is hingedly and vibratably supported. The outer free end of the arm 51 is provided with an electrical contact button 65 which is adapted to contact at times a similar button 66 formed preferably of a different metal than the button 65. The contact 66 is carried on a standard or terminal 67, said contact and said terminals being more particularly described in the said co-pending application.

As thus described it will be noted that the door 35 may be swung open and the core part 43 adjusted without removing the cover 26 or breaking the sealing wax 23 while at the same time the mechanism within the housing is protected from damage and also a tampering with said mechanism by unskilled persons is prevented.

I claim:

1. A housing for voltage regulators comprising a supporting base, a slab of electrically insulating material disposed on said base, securing members connecting the slab and base at points spaced from the edges of the slab, said slab having a groove extending about its entire edge between the securing members and the slab edge, a cover having top and side walls and an open bottom, the lower edges of said side walls being received in the groove in the slab, said top having a recessed portion with an aperture therein spaced from the side walls of the recess, one of said side walls having an opening therein, an indicator cooperating with said opening, a door secured to the side wall adjacent said opening and movable to cover and uncover the opening, a bolt extending through the recess aperture, cover and slab and secured to the supporting base, the bolt having a head disposed in the recess below the top thereof, and said bolt firmly securing the cover to the slab and plate, and sealing means disposed within said recess for sealing the bolt head in the recess.

2. The combination with a voltage regulator comprising a pre-adjusted sealed part and an adjustable part provided with a dial, of a housing

therefor comprising a supporting plate, a slab of electrically insulating material having a perimetrical portion engaging said plate and an intermediate portion spaced from said plate, said intermediate portion of said slab being adapted to support the voltage regulator parts, securing members connecting the slab and base at points spaced from the edges of the slab, said slab having a groove extending about its edge between the securing members and the slab edge, a cover having top and side walls and open bottom, the lower edges of said side walls being received in the groove in the slab, said top having a recessed portion with an aperture therein spaced from the side walls of the recess, one of said side walls having an opening therein adjacent the voltage regulator dial, an indicator cooperating with the dial, a door secured to the side wall adjacent the opening and movable to cover and uncover the opening, a bolt extending through the recess aperture, cover and slab and secured to the supporting base, the bolt having a head disposed in the recess below the top thereof, said bolt firmly securing the cover to the slab groove, and sealing means disposed within the recess for sealing the bolt head in the recess.

CHARLES W. MUSSER.
